UNITED STATES PATENT OFFICE

170,788

DISH OR THE LIKE

Eva Zeisel, New York, N. Y., assignor to Midhurst
China Company, Inc., New York, N. Y., a corporation of Ohio

Application August 29, 1952, Serial No. 21,230

Term of patent 14 years

(Cl. D44—10)

To all whom it may concern:

Be it known that I, Eva Zeisel, a citizen of the United States, residing in New York, New York, have invented a new, original, and ornamental Design for a Dish or the like, of which the following is a specification, reference being had to the accompanying drawing forming part thereof.

Fig. 1 is a perspective view of a dish or the like, showing my new design;

Fig. 2 is a side elevational view thereof; and
Fig. 3 is an end elevational view thereof.

I claim:

The ornamental design for a dish or the like, substantially as shown.

EVA ZEISEL.
